Attorney.

UNITED STATES PATENT OFFICE

MAX WENZEL, OF MULDENSTEIN, NEAR BITTERFIELD, GERMANY

ROLL SUCTION DEVICE

Application filed July 7, 1928, Serial No. 290,932, and in Germany April 13, 1928.

This invention relates to suction boxes and with regard to certain more specific features, to suction boxes such as are used in paper-making machinery.

5 Among the several objects of the invention may be noted the provision of suction boxes for paper machinery rolls in which an independent suction box is had for each roll, whereby a greater plurality of steps of suction action may be employed and a better distribution of suction effected over a suction area. Other objects will be in part obvious and in part pointed out hereinafter.

10 The invention accordingly comprises the elements and combinations of elements, features of construction, and arrangements of parts which will be exemplified in the structure hereinafter described, and the scope of the application of which will be indicated in 15 the following claims.

In the accompanying drawings, in which is illustrated one of various possible embodiments of the invention,

Fig. 1 is a longitudinal section through a 20 suction box, certain portions being shown in elevation;

Fig. 2 is a cross section taken substantially on line 2—2 of Fig. 1, certain portions being shown in elevation;

30 Fig. 3 is a top plan view of a plurality of rolls, certain portions being broken away to show the suction boxes;

Fig. 4 is an enlarged front elevation showing certain structural details;

35 Fig. 5 is a detailed section taken through a slide and packing plate;

Fig. 6 is a plan view of the parts shown in Fig. 5, a certain sieve or conveyor being removed; and

40 Fig. 7 is a plan view of certain bottom portions, the same being broken away to show certain packing means.

Similar reference characters indicate corresponding parts throughout the several 45 views of the drawings.

The present invention is an improvement on the type of machine set out in my United States Patent 1,518,116 and my German Patent 401,935, the latter issued September 15, 50 1924. As this art shows, it comprises a known

method to dispose the supporting rolls which carry the conveyor sieve above suction boxes, by means of which a partial vacuum is made to function over the surface of the sieve so as to tend to draw water from a layer of paper spread out thereon. However, it will be noted that in the prior art devices two or more supporting rolls are in communication with a common suction box. This arrangement has the disadvantage that each suction unit while operable in itself, comprises at least two suction areas or fields. Suction area or field is understood to mean that area of the sieve which is located between two supporting rolls and exposed to the partial vacuum. The above statements may be found to be true by reference to Fig. 1 of said United States patent.

I have found that it is desirable that the suction areas in serial arrangement should be operated severally, that is, independently of each other, so that they may either be added severally or be eliminated severally. According to the present invention, this object is to be accomplished by uniting each supporting roll independently with a suction chamber and a packing device so as to form a self-contained suction unit. Owing to this particular new and improved construction, one or two or any desired number 80 of suction units, comprising a supporting roll with pertaining suction box, may be arranged serially as desired in accordance with the requirements of any given paper machine. A further advantage is that in accordance with the progressive elimination of water from the web of paper being treated, each suction box or each suction area is operated at a progressively increasing partial vacuum, instead of having the vacuum increase only by steps each comprising a plurality of units at a time.

Referring now more particularly to the drawings, it will be noted that the suction boxes *f* are supported laterally on the side beams *g*. Each suction box *f* carries two bottom members or end pieces *e* in which bearing brackets *c* are supported and secured therein by suitable screws (not shown), said bearing brackets containing the bear-

ings *d* for rotatably supporting the supporting rolls *b*. The purpose of the end pieces *e* is to close the space between and around the ends of the rolls *b*. As illustrated in Fig. 1 and described in said Patent 1,518, 116, the slight opening between the rolls and the end pieces *e* are sealed by means of a water dam or seal. The supporting rolls *b* support the movable sieve *a* which in turn 10 supports the wet paper. On one of the longitudinal walls *u* of each suction box *f* a packing cleat *h* composed of several sections is secured. The packing cleat *h* extends over the entire distance between the end pieces *e*. 15 at both sides. Flexible rubber mats *i* are mounted on projections *w* of the upper parts of the packing cleats *h*, extending over the entire length between the slides or gates to be described, said mats engaging the sieve *a* and stripping off the water drawn from the pulp and which water drips through said sieve.

Slides or gates *k* are slidably supported on the end portions *c* so as to be movable 25 in the direction of the axes of the supporting rolls. These slides have sealing pads *x* engaging adjacent rolls. At the inner edge of each slide or gate *k*, is secured a flexible lip *l* made preferably of rubber and which 30 is directed upward towards the sieve (see Figs. 4 and 5). This lip *l*, occupies the space between the sieve *a* and the rigid margin of the slide or gate, and being yieldable, this 35 flexible lip will adapt itself to the sag of the sieve between rolls. The end portions *e* are slightly narrower than the suction boxes *f*, so that upon serially placing the suction boxes, gaps *p* will remain (Fig. 7). This arrangement has the object of facilitating 40 the serial disposition of the self-contained suction unit. The gap *p* is filled by yielding packing means. It is of advantage to 45 provide packing grooves *m* in opposite lateral surfaces of the bottom portions *e* in such manner that these packing grooves *m* are filled in subsequent to the serial placement 50 of the suction units and for the purpose of filling in these grooves, packing cord or a packing mass may be used. The end members *e* are provided in their lateral walls with perforations *q* between the packing strips, permitting the passage of sealing water between the various end members.

Each suction chamber *f* is arranged to conduct away separately the water on one side 55 by a pipe extension *n* and the air on the other side by the pipe *o*. The pipe for withdrawing the air projects up with the extension *j* in the suction box, above the level of the water, and is protected by the hood *r* against the entry of drip or splash water. If it is desired, two or more of these suction units 60 may be operated at uniform partial vacuum, and the perforations *s* may be disposed in 65 the longitudinal walls for the water, while

the perforations *t* are arranged for the air so that the suction boxes to be operated together are in communication with each other, and so that a common discharge of water or air is made possible. This feature however is not necessary where each box is being operated at a different vacuum. 70

It is to be understood that a suitable seal is effected between the packing cleats *h* and the rolls *b* by reason of the water entrained on the rolls, the distance between the engaging face *v* and the roll being short. Openings *w* (Fig. 2) permit communication between the rolls so that each suction box effects a vacuum field over only that part of the sieve 80 suspended between one pair of rolls. 75

It will be seen from the above that each roll chamber is sealed along the roll at the face *v*, at the ends of the roll by the dam ends *e*, the only remaining seal necessary, being effected by the slides or gates *k* with the rubber lips *l*. 85

The purpose of making the gates *k* slid- 90 able is to accommodate various widths of sieves *a* for various widths of paper. It will be noted that each roll and cooperating suction box comprises a self-contained structure adapted to be abutted with the next structure for making up any number in a series.

In view of the above, it will be seen that 95 the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense. 100

I claim:

1. In a roll suction device for paper machines and the like, in combination, a sieve, rotary rolls for supporting said sieve, a plurality of suction chambers, one associated with each roll and sealing means between each roll and each chamber comprising longitudinal roll packing cleats, end members for sealing the ends of the rolls with slide gates for completing the seal. 110

2. In a roll suction device for paper machines and the like, in combination, a sieve, rotary rolls for supporting said sieve, a plurality of suction chambers, one associated with each roll and sealing means between each roll and each chamber comprising longitudinal roll packing cleats, end members for sealing the ends of the rolls with slide gates for completing the seal, said gates cooperating between adjacent rolls and having flexible portions engaging the sieve. 120

3. In a roll suction device for paper machines and the like, in combination, a sieve, rotary rolls for supporting said sieve, a plurality of independent suction chambers, one 130

associated with each roll and means whereby each suction chamber effects a single suction area over the sieve.

4. In a roll suction device for paper machines and the like, in combination, a sieve, rotary rolls for supporting said sieve, a plurality of independent suction chambers, one associated with each roll and means whereby each suction chamber effects a single suction area over the sieve, which area is bounded by adjacent rolls.

5. In a roll suction device for paper machines and the like, in combination, a sieve, means for supporting said sieve comprising rolls, a plurality of independent suction boxes formed to support said rolls, each roll and suction box therefore comprising a self-contained and independently movable structure, means for effecting a seal between each box and each roll so that independent suction areas may be effected between the successive rolls.

6. In a roll suction device for paper machines and the like, in combination, a sieve, means for supporting said sieve comprising rolls, a plurality of independent suction boxes formed to support said rolls, each roll and suction box therefor comprising a self-contained and independently movable structure, means for effecting a seal between each box and each roll so that independent suction areas may be effected between the successive rolls, means for communicating between successive suction boxes and means for sealing the communications against leakage.

In testimony whereof, I have signed my name to this specification this 8th day of June, 1928.

MAX WENZEL.
